DESCRIPTION

FIG. 1 is an isometric view of an electronic candle with a retractable flame element, with the retractable flame element shown in a protruding position;

FIG. 2 is a front view of the electronic candle of FIG. 1;
FIG. 3 is a back view of the electronic candle of FIG. 1;
FIG. 4 is a left view of the electronic candle of FIG. 1;
FIG. 5 is a right view of the electronic candle of FIG. 1;
FIG. 6 is a top view of the electronic candle of FIG. 1;
FIG. 7 is a bottom view of the electronic candle of FIG. 1.
FIG. 8 is another isometric view of the electronic candle of FIG. 1, showing an alternate position of the retractable flame element in a retracted position;

FIG. 9 is a front view of the electronic candle of FIG. 8;
FIG. 10 is a back view of the electronic candle of FIG. 8;
FIG. 11 is a left view of the electronic candle of FIG. 8;
FIG. 12 is a right view of the electronic candle of FIG. 8;
FIG. 13 is a top view of the electronic candle of FIG. 8; and,
FIG. 14 is a bottom view of the electronic candle of FIG. 8.
The broken-line disclosure represents portions of the electronic candle with a retractable flame element which form no part of the claimed design.
